United States Patent

Des. 235,536
Patented June 24, 1975

235,536

DETACHABLE SUNROOF FOR A PASSENGER VEHICLE

Andrew W. Boston, Jr., 4618 Rodeo 90016, and Lance M. Porter, 1116 W. 96th St. 90044, both of Los Angeles, Calif.

Filed June 11, 1973, Ser. No. 368,765

Term of patent 14 years

Int. Cl. D12—16
U.S. Cl. D12—156

Fig. 1

Fig. 2

Fig. 3

Fig. 4

FIG. 1 is a top perspective view of a detachable sunroof for a passenger vehicle embodying our new design.

FIG. 2 is a bottom plan view thereof.

FIG. 3 is an inboard side elevational view thereof; and FIG. 4 is a rear end elevational view thereof.

We claim:

The ornamental design for a detachable sunroof for a passenger vehicle, substantially as shown.
